UNITED STATES PATENT OFFICE.

WILLIAM H. MUZZY, OF DAYTON, OHIO.

REISSUED

FUEL-FEEDING DEVICE FOR AUTOMOBILES.

1,201,077.

Specification of Letters Patent. Patented Oct. 10, 1916.

Application filed March 20, 1915. Serial No. 15,895.

To all whom it may concern:

Be it known that I, WILLIAM H. MUZZY, a citizen of the United States, residing at Dayton, in the county of Montgomery and State of Ohio, have invented certain new and useful Improvements in Fuel-Feeding Devices for Automobiles, of which I declare the following to be a full, clear, and exact description.

10 This invention relates to improvements in motor vehicles and has more particular relation to improvements in mechanisms, systems and devices for the feeding of liquid gasoline to the carbureters of explosive gas engines.

One of the objects of the invention is the improvement of the devices and mechanisms at present employed in the so called "vacuum systems" for feeding gasoline 20 from a relatively low supply tank to the carbureter of the engine.

Another object of the invention is the elimination in my improved tank of all floats, float valves, flap valves and other 25 similar mechanical valves which are subject to misoperation and derangement from the presence of small particles of dirt or other foreign matter in the gasoline or from wear.

30 A further object of the invention is the elimination of all movable parts which as is well known are subject to misoperation and derangement from the vibration and jars they are subjected to when used in connection with motors and motor cars.

A still further object of the invention is to utilize the vacuum to raise the gasoline to a gravity feed tank and to control its feed from such tank to the carbureter by 40 the presence or absence of the gasoline within the gravity tank without any movable mechanical devices.

In carrying these and other objects of the invention into effect I utilize certain 45 constructions, combinations and arrangements of parts all of which will be herein-after more particularly set forth and claimed.

In carrying out my invention in its preferred form of embodiment I have shown in the accompanying drawings certain constructions and combinations but it will be readily understood that these may be varied and other similar devices employed

without departing from the spirit of this 55 invention.

In the aforesaid drawings: Figure 1 represents, in side elevation, a gas engine, parts of the chassis, the carbureter, the main gasoline tank and my improved 60 vacuum and siphon tank and connections and, Fig. 2 represents a detail vertical section through my improved vacuum and siphon tank and connections.

In general terms the invention may be 65 described as utilizing part of the suction in the intake manifold of the engine to create a vacuum in a small tank secured to the dash board of the machine above the engine and thus draw the gasoline from the 70 main supply tank at the rear up into this vacuum tank. The gasoline is then fed by gravity from this vacuum tank or chamber to an intermediate trap or chamber and then from this latter chamber by a siphon 75 into a chamber which supplies the carbureter by gravity. When the level of the gasoline in the carbureter supply chamber falls too low the lower end of an air pipe in this chamber is uncovered and air rushes 80 through this pipe into the upper end of the vacuum chamber and relieves the vacuum. The gasoline then flows by gravity from the vacuum chamber to an intermediate chamber and from this latter 85 chamber to the carbureter supply chamber until the lower end of the air pipe is again closed when the vacuum is again established and a fresh supply of gasoline is drawn from the main tank. When the 90 vacuum is broken as above described all surplus gasoline flows back into the main tank at the rear.

In the before mentioned drawings 2 represents the vacuum tank, 3 the air suction 95 pipe of the same, 24 the carbureter, 25 the intake manifold, 27 the main gasoline tank at the rear of the machine, 23 the supply pipe for the carbureter, 7 the pipe connecting the vacuum tank and the main tank 100 and 9 the breather pipe of the vacuum tank.

The pipe 3 connects at one end to the manifold 25 and at its opposite end to the detachable cover of the tank 2.

An obstructing wall 4 having a small aperture therein is mounted in the pipe 3 to cause the right amount of suction to be

exerted in the chamber 1. The size of the aperture in this wall is determined by the type of engine with which my invention is to be used but after being once determined it remains fixed and set. An ordinary ball check valve 5 is also mounted in the pipe 3 to prevent any air passing back through this pipe in the opposite direction from the suction.

10 The chambers 1, 10 and 15 of the tank are formed by horizontal partitions 13 and 14 suitably secured in the tank. The chambers 10 and 15 are open to the air at all times by means of a vent pipe 9 connected 15 to them by short pipes 18 and 19.

15 The main supply pipe 7 is connected to the bottom of the tank 27 at one end and at its opposite end enters the chamber 1 and projects upward into the same about 20 two thirds of its height. By this means there is always sufficient gasoline in the chamber 1 to more than fill the chamber 10 and to supply the gasoline used from the chamber 15.

25 The gasoline when relieved of the vacuum flows from the chamber 1 down through the pipe 11 until the chamber 10 is almost filled. The gasoline then starts to flow through the siphon 12 into the pan 16 fast 30 to the side wall of the chamber 15. The gasoline flows through an aperture 17 in the bottom of this pan and raises the level of the gasoline in the chamber 15 until the lower end of the pipe 8 is covered. This 35 pipe projects from near the bottom of the pan 16 to near the top of the chamber 1 and is an air vent pipe for relieving the vacuum in the chamber 1, so that when the lower end is covered the air is cut off from the chamber 1 and the vacuum is again established. The gasoline is drawn up the pipe 8 into the chamber 1 until the level of the gasoline in the chamber 15 descends 40 sufficiently to permit air to again pass up the pipe 8 when the vacuum is again relieved and the gasoline again passes down the pipe 11 and the operation is repeated. Just as soon as the gasoline covers the lower end of the pipe 8 part of the gasoline 45 50 in the chamber 10 is drawn up through the pipe 11 but the gasoline continues to flow through the siphon 12 until the level in the chamber 10 reaches the lower end of the siphon in said chamber. The diameter of the siphon pipe 12 is greater than that of the pipe 8 and a large stream of gasoline is thus fed to the chamber 15 and completely fills the pipe 8 which draws it up into the chamber 1 as before described. When the pumping action starts gasoline is being drawn from the main feed pipe 7, from the pipe 11 and from the pipe 8 but as the end of the siphon in the chamber 10 is above the lower end of the pipe 11 the latter will 55 60 65 continue to draw or be covered while the air

will start up through the pipe 8 and thus relieve the vacuum again. Any gasoline that is above the upper end of the pipe 7 when the vacuum is relieved will pass down the pipe 7 and back to the main tank.

The office of the pan 16 is to prevent the gasoline in the chamber 15 from slopping up against the lower end of the pipe 8 because of the motion of the car and thus preventing the free passage of air through this pipe.

A guard plate 6 is suspended from the cover of the tank leaving a passage at one side and to prevent the streams from the pipes 8 and 7 and the splash from the chamber 1 from entering the pipe 3. The construction and capacities of the several chambers are such that the level of the gasoline never goes above the upper end of the pipe 8. The cross sectional areas of pipes 8 and 11 are so restricted that when they are full of gasoline the chamber 1 is practically sealed and the suction through pipe 3 will create a vacuum sufficient to raise the gasoline from the tank 27. This continues as long as pipes 8 and 11 are full of gasoline as the liquid cannot escape from them into the chamber 1 fast enough to counteract the vacuum being created by the intense suction from the pipe 3.

The operation of the tank is entirely automatic and continuous, the gasoline being first drawn into chamber 1, then allowed to descend to chamber 10, then partly siphoned to chamber 15 and finally drawn into chamber 1 again. Each time that the gasoline is drawn into the chamber 1 the pipe 7 will feed more gasoline than the engine is using, this surplus each time passing down the pipe 7 again, that is after the level of the gasoline in the chamber 1 reaches above the upper end of the pipe 7.

The pipe 23 which connects chamber 15 to the carburetor is provided with any ordinary valve 21 for opening and closing the pipe at will. This valve is operated by a rod 22 which projects through the dashboard 26 and is provided with an operating knob. This valve 21 is a night valve and is supposed to be used if desired, when the machine is left standing for any great length of time to prevent the escape of gasoline from the chamber 15. This escape of gasoline would only be possible however if the machine had a leaky float valve in the carburetor.

It will also be understood that while I have provided the guard plate 6 to prevent gasoline entering the pipe 3 many other constructions may be employed that would accomplish the same result.

It will be observed that with my improved construction of tank the pipe 3 is always drawing a constant stream of air saturated with gasoline gases which have been created

by the agitation of the gasolene in the chambers 1 and 15 and that for this reason the imperfect operation of the engine is not interfered with after the carburetor is once set in accord with this mixture.

5 It will be understood that the check valve 5 is not essential to the operation of my improved tank but it gives a more even suction on the feed pipe 7. The suction on the 10 pipe 3 is strong enough to raise the gasolene from the main tank 27 in a spouting stream not only when the machine is on a level but also when it is climbing a 45 per cent. grade. The location of the tank 2 in relation to the 15 tank 27 is such however that when the machine is going down a grade the chamber 1 of the tank is always higher than the tank 27.

Having thus described my invention what 20 I claim as new and desire to secure by Letters Patent is:

1. In a fuel feeding system the combination with an elevated tank having a vacuum chamber and a supply chamber, means for creating a vacuum in the vacuum chamber, an air vent for the vacuum chamber sealed and unsealed by the liquid fuel in the supply chamber, a main supply tank connected to the vacuum chamber, and connections between the vacuum chamber and the supply chamber.

2. In a fuel feeding system the combination with a main tank, of an elevated vacuum tank having a vacuum chamber and a supply chamber, means for creating a vacuum in the vacuum chamber, an air vent for the vacuum chamber sealed and unsealed by the liquid fuel in the supply chamber, means connecting the main tank and the vacuum chamber and means intermediate the vacuum chamber and supply chamber, for delivering fuel to the latter irrespective of the suction in the former.

3. In a fuel feeding system the combination with a main tank, of an elevated vacuum tank having a vacuum chamber and a supply chamber, stationary means connecting the two chambers for allowing liquid

fuel to pass to the supply chamber without allowing air to pass to the vacuum chamber, 50 an air vent for the vacuum chamber sealed and unsealed by the liquid in the supply chamber, means connecting the main tank and the vacuum chamber, and means for creating a vacuum in the vacuum chamber. 55

4. In a fuel feeding system the combination with a main tank, of an elevated vacuum tank having a vacuum chamber, a supply chamber, and an intermediate chamber, an air vent for the vacuum chamber sealed 60 and unsealed by the liquid fuel in the supply chamber, a siphon in the intermediate chamber discharging into the supply chamber, connections between the vacuum chamber and intermediate chamber, means connecting the main tank to the vacuum chamber, and means for creating a vacuum in the vacuum chamber. 65

5. In a fuel feeding system the combination with a main tank, of an elevated vacuum tank connected thereto and having a vacuum chamber, and a supply chamber, stationary fuel feeding and air vent means connecting the vacuum and supply chambers, said means being sealed and unsealed 75 by the liquid fuel, and means for creating a vacuum in the vacuum chamber.

6. In a fuel feeding system the combination with an elevated tank having a vacuum chamber and a supply chamber, means for creating a vacuum in the vacuum chamber, a main tank, a feed pipe connecting this tank and the vacuum chamber, a discharge pipe for the vacuum chamber arranged to be sealed by the liquid fuel to 80 prevent air passing into the vacuum chamber, and an air pipe extending up into the vacuum chamber and arranged to be sealed by the liquid in the supply chamber.

In testimony whereof I affix my signature in the presence of two witnesses.

WILLIAM H. MUZZY.
